(57) **CLAIM**

The ornamental design for tablet computer, as shown and
described.

DESCRIPTION

FIG. 1 is a top front perspective view of tablet computer
showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a reference view thereof when the front and rear
boards are opened;

FIG. 9 is reference view thereof when they are semi-opened;
and,

FIG. 10 is a reference view thereof when they are linked
horizontally by using a rotational hinge, shown on a support
base.

The both display screens in the inner sides of the front and
rear boards of the present design tablet computer are touch-
screen types.

The front and rear boards of the present tablet computer are
linked by both the left hinge and the rotational hinge. Accord-
ingly, the front and rear boards are opened by using the left
hinge (see FIGS. 8 & 9). Also, the front and rear boards are
linked horizontally like a TV by using the rotational hinge
(see FIG. 10).
